GAME BOARD

Paul S. Collignon, 6710 N. Riley, Indianapolis, Ind.

Filed Apr. 10, 1961, Ser. No. 64,680

Term of patent 3½ years

(Cl. D34—5)

FIG. 1 is a plan view of a game board embodying my new design.

The game board is of conventional thickness.

The characteristic feature of my design resides in the pattern formed by a series of 5 superposed quadrangular patterns arranged on a grid-like background, the outermost pattern being square having circles in each corner, the next inner pattern is a square set at an angle to the outer and having squares at the corners, the next inner pattern is rectangular set at an angle to the next outer and having rectangles at the corners, the next inner pattern is square set at an angle to the next outer and having triangles at the corners, the next inner pattern is square set at an angle

to the next outer and having rhombuses at the corners, all as shown.

I claim:

The ornamental design for a game board, as shown and described.
